UNITED STATES PATENT OFFICE.

OTIS A. MYGATT, OF NEW YORK, N. Y.

DESIGN FOR AN ILLUMINATOR.

No. 37,946.

Specification for Design.

Patented April 10, 1906.

Application filed July 14, 1905. Serial No. 269,733. Term of patent 14 years.

To all whom it may concern:

Be it known that I, OTIS A. MYGATT, a citizen of the United States, residing at New York, in the county of New York and State of New York, have invented a certain new, original, and ornamental Design for Illuminators, of which the following is a specification, reference being had therein to the accompanying drawings, forming part thereof.

Figure 1 is a side elevation of the illuminator. Fig. 2 is a perspective view from a plane somewhat below the illuminator.

The socket or holder of the illuminator is of opaque material. The flared bell is of transparent glass. The bulb appearing below the bell is frosted glass.

I claim—

The ornamental design for an illuminator, as shown and described.

OTIS A. MYGATT.
